OUTLET GRILLS FOR AIR CONDITIONERS

Shannon L. Madison, York, Pa., assignor to Borg-Warner Corporation, Chicago, Ill., a corporation of Illinois

Application January 23, 1958, Serial No. 710,701

3 Claims. (Cl. 98—40)

This invention relates to room air conditioners and particularly to a louvered air outlet grill for directing the flow of air therefrom.

In order to get proper circulation of air in a room to be conditioned and proper comfort conditions for the occupants thereof, it is necessary that the air discharging from a room air conditioner be capable of having its direction of flow varied at will in order that it may be accommodated to various locations within the room to be conditioned and respond to the individual preferences. While many such devices have been proposed in the past and performed satisfactorily, they all suffered from a common defect in that they were generally cumbersome, difficult to fabricate and correspondingly expensive.

It is an object of the invention, therefore, to provide, expeditiously and at low cost, a louvered air outlet grill for directing the air flow from a room air conditioner, and which controls both the vertical and horizontal direction of the air.

It is a further object to provide an apparatus of the above nature, which is sturdy and practical in construction, efficient and dependable in use, of a minimum number of parts, and easily and inexpensively fabricated. These and other objects will be in part obvious and in part pointed out below.

The invention consists of the novel constructions, arrangements and devices to be hereinafter described and claimed for carrying out the above-stated objects and such other objects as will appear from the following description of preferred embodiments of the invention described with reference to the accompanying drawings, in which:

Fig. 1 is a perspective of a room air conditioner embodying a pair of the louvered air outlet grills;

Fig. 2 is a view in perspective of two such grills;

Fig. 3 is a detail of the air conditioner of Fig. 1 showing a grill control knob;

Fig. 4 is a vertical sectional view of the air outlet of the air conditioner and showing the assembled grills and control knobs in operative position therein and taken on the line 4—4 of Fig. 3;

Fig. 5 is a plan of the air conditioner shown in Fig. 1 with a portion of the cover thereof broken away in order to better show details of the outlet grills mounted therein;

Fig. 6 is a view in vertical section showing the method of mounting the outlet grills in assembled relation in the air conditioner taken on the line 6—6 of Fig. 5 but in enlarged section;

Fig. 7 is a view taken on the line 7—7 of Fig. 6;

Fig. 8 is a plan and Fig. 9 is a vertical view of an air-flow directing louver mounted in its framework and before rotation thereof to its final desired position;

Fig. 10 is a plan and Fig. 11 is a vertical view of the louver of Figs. 8 and 9 rotated within its framework to its desired position; and

Fig. 12 is a perspective view of the louver of Figs. 10 and 11.

Turning now to the drawings and particularly Fig. 1 thereof, a room air conditioner is indicated generally at 20 and has an air outlet 21 therein. Air outlet 21 is in part formed in a front wall 22 of the unit and in part formed in a top wall 23 of the unit.

Air outlet 21 is suitably enclosed by a decorative cover indicated generally at 24.

2

The air conditioner 20 is further provided with a left-hand grill support 25 having an aperture 26 therethrough, a right-hand grill support 27 having an aperture 28 therethrough and a central grill support 29 having an aperture 30 therethrough.

A pair of louvered air outlet grills 31 are rotatably mounted within the air conditioner 20 for directing the flow of air through air outlet 21. The grills 31 are identical and interchangeable within the air conditioner. Each grill includes a pair of frame members 32 and 33 maintained in the proper spaced relationship by a pair of supporting members 34 and 35. Support members 34 and 35 each includes two semi-circular recesses 36 and two slightly larger recesses 36'. As can clearly be seen in Fig. 2, a plurality of air flow directing louvers 37 are mounted between respective frame members 32 and 33.

As was pointed out above, and in order to save costs, each air outlet grill is identical, there being no left-hand or right-hand members, as might be expected. Each grill has on the support member 34 thereof a male lug 38 and on the other support member 35 thereof a female lug receiving recess 39. Means for rotating the grills are provided and take the form of control knobs 40 for receiving one end of a grill for rotating each individually. Control knobs 40 comprise a wheel-like element 41 having a series of beads 42 formed thereon in order to facilitate handling. Wheel-like element 41 has a bearing 43 formed on the outer surface thereof and terminates in a lug 44. Internally, the wheel-like element 41 is provided with a bore 45, which bore is designed to receive the lug 38 of a grill 31. The inner surface of wheel-like element 41 is further provided with two outstanding pins 46, adapted to be received in the semi-circular recesses 36 formed in supporting members 34 and 35, and two outstanding pins 46' adapted to be received in the semi-circular recesses 36'.

It will be apparent that in assembling two louvered air outlet grills 31, since the lug 38 of one is received in the recess 39 of the other, as seen in Fig. 6, the free ends thereof include on one side a lug 38 and on the other side a recess 39. In assembling the control knobs 40 with the assembled grills 31, again with references to Fig. 6, it will be seen that a bore 45 of a knob 40 receives a lug 38 while on the other end thereof a bore 45 is opposed by a recess 39 which, of course, offers no impediment to the placing of the control knob 40 thereon, thereby permitting the grills to be interchangeable.

The method of properly mounting each louver between its frame members will be more clearly described with reference to Figs. 8—11. As can clearly be seen in Figs. 8 and 9, a louver blank 37' is first obliquely mounted with respect to frame members 32 and 33, hereinafter defined as being in an "oblique plane" with respect to said frame members. Louver blank 37' is then canted, or rotated from its position shown in Figs. 8 and 9 to a position wherein the trace of said louver on said frame members with respect to the intersected edges thereof form an oblique angle, as shown at "B" in Fig. 10, hereinafter defined as being in a "canting plane" with respect to said frame members. This provides the desired deflection (both horizontal and vertical) of air flow when the grill is in a vertical position, as seen in Fig. 11.

After the louver blank 37' has been canted or rotated to its desired position, as shown in Figs. 10 and 11, it is apparent that in order to be properly fitted between frame members 32 and 33 it must be cut to take the form of a parallelogram, as shown in Fig. 12. As can be seen in Fig. 12, the edges of the louver blank 37' are then properly beveled in order that they may lie in horizontal and vertical planes in the canted position of the louvers themselves to form the finished louver 37.

The angle "A" shown in Figs. 9 and 11 is a measure of the inclination of a louver 37 from the horizontal. The angle "B" as shown in Fig. 10 is a measure of the canting or rotation of a louver 37 and decreases as the louver is rotated with the angle of cant correspondingly increasing.

It has been found empirically that the desired angle "A" should be on the order of 30°. It has been determined empirically that the angle "B" should be on the order of 45°. This combination has been found to give the best horizontal and vertical control of the air flow with the minimum pressure drop through the grill 31 due to the canting of the louvers.

The width "w" of a louver 37 must be found empirically and is dependent on (1) the velocity of the air discharging from the outlet 21 of air conditioner 20, (2) the total number of louvers, and (3) the angle of cant. The higher the velocity is, the greater the width "w" must be in order to change the direction of flow. As the number of louvers increases, the width "w" may decrease to give the desired change in direction of flow; however, it must be borne in mind that as the number of louvers increases, the pressure drop through the grill correspondingly increases. It will also be apparent that the greater is the angle of cant (the supplement of angle "B," as seen in Fig. 10), the greater must be the width "w" in order to change the direction of flow.

As many louvers as has been found desirable are mounted between frame members 32 and 33. As can be seen in Fig. 2, it may be oftentimes necessary to mount a louver between a frame member 32 or 33 and its corresponding support member 34 or 35 in order to maintain the desired spacing between louvers. However, in referring to a louver being mounted between frame members, the term is considered to be all-encompassing and including the mounting of a louver between a frame member and a corresponding support member.

In assembling the grills in air conditioner 20, one grill 31 has a control knob 40 mounted thereon, as seen in the right hand portion of Fig. 6. The control knob 40 is mounted on a support member 35 having recess 39 therein and pins 46 are received within semi-circular recesses 36, while pins 46' are received within recesses 36', to maintain knob and grill in proper assembled relation. The grill supports 27 and 29 are then flexed sufficiently to permit the insertion of the assembled grill and knob with lug 44 of knob 40 being received in aperture 28 of grill support 27 and lug 38 of grill 31 being received in aperture 30 of grill support 29. Similarly, a knob 40 is assembled with a grill 31, as shown in the left hand portion of Fig. 6 with pins 46 and 46' being received in recesses 36 and 36' respectively. However, in this instance, the knob 40 is mounted on a support member 34 including a lug 38, with lug 38 being received within bore 45 of knob 40. Grill support 25 is then sufficiently flexed to allow the insertion of the assembled knob and grill between it and grill support 29 with the lug 44 of knob 40 being received in aperture 26 of grill support 25 and recess 39 receiving the lug 38 of the previously inserted grill 31.

The purpose of having pins 46 and corresponding recesses 36 differ in size from pins 46' and corresponding recesses 36' is that the control knobs 40 may be mounted on the grills in only one position so that the indicia printed on the control knobs (as seen in Fig. 3) may be properly oriented with respect to the grills. It will be further noted that the control knobs are interchangeable, at least until such time as the indicia is printed thereon.

Turning now to Fig. 2, an inspection of the right-hand grill 31 reveals that it is in position to direct the air upwardly and to the left. The left-hand grill has been rotated approximately 180° from the position of the right-hand grill and in a position to direct the air upwardly and to the right. It will be apparent that any one grill (refer to Fig. 2), during a complete 360° revolution

thereof directs the air upwardly and to the right (assuming this initial horizontal deflection), horizontally and to the right and downwardly and to the right; upwardly and to the left (in the opposite direction to the initial horizontal deflection), horizontally and to the left and finally downwardly and to the left during the course of its rotation.

Canting the louvers 37 from the position shown in Fig. 9 to the position shown in Fig. 11 serves two functions. The average person will position the grill 31 in its vertical position, as seen in Fig. 11, and let it remain there. In this position, if the louvers were not canted as shown in Fig. 11 but left instead as shown in Fig. 9, then it can be seen that the air would discharge straight out through the grill, there being neither a horizontal nor a vertical deflection. Canting the louvers 37, however gives a desired vertical and horizontal deflection to the air passing through the grill 31 when the grill is in its normal vertical position (as seen in Fig. 11). Further, with the louver left uncanted, in order to get a desired deflection of air comparable to the deflection obtainable from the canted louver, it would be necessary to rotate the grill to where it would approach the position shown in Fig. 8 or, in other words, a 90° rotation. It is, of course, apparent that the more closely the grill approaches the Fig. 8 position, the greater is the blockage of air by frame members 32 and 33, with the greatest blockage occurring when the grill is in the Fig. 8 position.

It will be apparent that I have provided a grill that is of extreme simplicity, of a minimum number of parts, adapted for mass production at an extremely low cost, and yet well capable of carrying out its intended function of directing the air flow from the outlet of a room air conditioner.

I wish it to be understood that my invention is not to be limited to the specific constructions and arrangements shown and described, except only insofar as the claims may be so limited, as it will be apparent to those skilled in the art that changes may be made without departing from the principles of the invention.

What is claimed is:

1. In a room air conditioner having an outlet for conditioned air, an air outlet grill for directing the flow of said conditioned air comprising, a pair of frame members, a pair of support members for maintaining said frame members in an assembled, spaced-apart, parallel relationship and a plurality of louvers obliquely mounted in parallel between said frame members, and rotated into canted planes with respect to the planes of said frame members; means for mounting said grill in the outlet of a room air conditioner; and a control member for rotating and determining the position of said grill for providing multiple flow paths for said conditioned air dependent on the positioning of said control member.

2. An air outlet grill for directing the flow of air through an air outlet of a room air conditioner comprising, a pair of frame members; a pair of supporting members attached to said frame members for maintaining said frame members in assembled, super-imposed, spaced-apart, parallel relation; and a plurality of louvers obliquely mounted in parallel planes between said frame members and rotated into canted planes with respect to said frame members.

3. The grill of claim 2 including, means for mounting said grill within the air outlet of a room air conditioner; and means for rotating said grill whereby a multiple selection of air flow paths is available upon the rotation of said grill.
